(57) **CLAIM**

The ornamental design for a battery swapping station as shown and described.

DESCRIPTION

FIG. 1 is a first perspective view of a battery swapping station;

FIG. 2 is a second perspective view of the battery swapping station;

FIG. 3 is a front elevation view of the battery swapping station;

FIG. 4 is a rear elevation view of the battery swapping station;

FIG. 5 is a left side elevation view of the battery swapping station;

FIG. 6 is a right side elevation view of the battery swapping station; and,

FIG. 7 is a top plan view of the battery swapping station.
